UNITED STATES PATENT OFFICE.

CHARLES W. NORRIS, OF CHICAGO, ILLINOIS.

GOLF-DRIVE TESTER.

Application filed January 10, 1923. Serial No. 611,812.

To all whom it may concern:

Be it known that I, CHARLES W. NORRIS, a citizen of the United States, residing at Chicago, in the county of Cook and State 5 of Illinois, have invented new and useful Improvements in Golf-Drive Testers, of which the following is a specification.

This invention relates to a device for testing the length of the drive of a golf 10 ball, and an object of the invention is to provide a golf drive tester which is applicable for either indoor or outdoor use, being particularly designed for indoor use.

Another object of the invention is to provide 15 a device of this character which may be used for practice, enabling the golfer to perfect his stroke by determining the yardage or distance obtained by different types of strokes and different amount of 20 power put behind the strokes.

A further object of the invention is to provide a golf drive tester which is comparatively simple in construction comprising a flexible member against which the ball 25 is driven and an indicator operatively connected to the flexible member and proportioned to accurately register the number of yards the ball would have traveled, by utilization of the force with which the ball 30 strikes the flexible member.

Other objects of the invention will appear in the following detailed description taken in connection with the accompanying drawings wherein:—

35 Fig. 1 is a front elevation of the improved golf drive tester.

Fig. 2 is a vertical section through the drive tester taken on the line 2—2 of Fig. 1.

40 Fig. 3 is a detail section on the line 3—3 of Fig. 2.

Fig. 4 is a horizontal section on the line 4—4 of Fig. 1.

45 Fig. 5 is a perspective view of a part of the tester structure.

50 Referring more particularly to the drawings the improved drive tester comprises a supporting frame 1, preferably constructed of angle iron or similar material. The supporting frame 1 includes the base 2, front frame 3 and rear frame 4. The front frame 3 which is rectangular shape in elevation inclines inwardly as it extends upwardly, and is open as clearly shown in Fig. 1 of the drawings, exposing the flexible 55 curtain 5 against which a golf ball may be driven, a baseball thrown or the like.

The flexible or canvas curtain 5 has its lower end attached to a rod 6 which is rotatably supported from the base 2 by suitable bearings 7. The upper end of the curtain 5 is braced by a rod 8, which rod is connected by means of arms 9 to a shaft 10. The shaft 10 is in turn rotatably supported by suitable bearings 11 and the arm 12 which also is connected to the rod 8 and to the shaft 10, has a crank arm 13 formed thereon. A ball or head 14 is formed on the outer end of the arm 13 and engages the movable block 16. The movable block 16 is movable in a vertical guide 17, as clearly shown in Fig. 4 of the drawings and it has an indicating hand 18 thereon which cooperates with graduations 19 on a dial or face board 20 which rises from the forward upper edge of the front frame 3. The graduations 19 are made to indicate linear distances.

The arm 13, and arms 9 and 12 are proportioned, in relation to the canvas or curtain 5 and indicator 16, to move the indicator along the graduations 19 a proportionate distance which the object which is driven against the curtain would travel, the said distance being measured by the force of impact of the object against the curtain 5. The force of impact of the object against the curtain 5 will tend to force the curtain rearwardly and move its upper edge downwardly, rocking the shaft 10 and forcing the indicator upwardly by the impact of the head 14 against the body 16.

55 A spring 21 is connected to the arm 12 for returning the curtain 5 to its normal taut position and also for returning the arms 12 and 13 to their normal positions.

It is to be understood that the indicator structure may be placed in a horizontal position and the hand be moved by a dial if so desired, without departing from the spirit of this invention.

60 It is, of course, to be understood that the invention may be constructed in other manners and the parts associated in different relations and, therefore, I do not desire to be limited in any manner except as set forth in the claims hereunto appended.

Having thus described my invention what I claim is:—

65 1. In a device as set forth, a supporting frame, an impact curtain having its lower edge anchored to said frame, an indicator hand and means connected to the upper

movable end of said impact member for striking and operating said indicating hand.

2. In a device as set forth, a flexible impact member anchored at its lower edge, the upper edge of said member being mounted for limited movement, an indicator hand, and means connected to said movable end of said impact member for striking and operating said indicating hand.
- 10 3. In a device as set forth, a supporting frame, an impact curtain having its lower edge anchored to said frame, a rockable shaft carried by said frame, arms connecting said rockable shaft to the upper edge of said curtain whereby the shaft will be rocked upon inward movement of the curtain under force of impact of an article thereagainst,

and indicating means adapted to be operated by rocking of said shaft.

4. In a device as set forth, a supporting frame, an impact curtain having its lower edge anchored to said frame, a rockable shaft carried by said frame, arms connecting said rockable shaft to the upper edge of said curtain whereby the shaft will be rocked upon inward movement of the curtain under force of impact of an article thereagainst, a striker arm carried by said shaft, and an indicator hand adapted to be operated by said striker arm upon rocking of said shaft.

In testimony whereof I affix my signature.

CHARLES W. NORRIS.
